TAP CONNECTOR FOR ELECTRICAL CONDUCTORS

James F. Turley, Cranford, and Edward L. Eldridge, Metuchen, N. J., assignors to The Thomas & Betts Co., Elizabeth, N. J., a corporation of New Jersey

Application August 14, 1956, Serial No. 42,600

Term of patent 14 years

(Cl. D26—1)

Fig. 3.

Fig. 4.

Fig. 5.

Fig. 1 is a view in perspective of a tap connector for electrical conductors, embodying our new design, taken from one side thereof;

Fig. 2 is a view in perspective taken from the opposite side thereof;

Fig. 3 is a transverse sectional view taken on the line 3—3 of Fig. 1;

Fig. 4 is a transverse sectional view taken on the line 4—4 of Fig. 2; and

Fig. 5 is a transverse section taken on the line 5—5 of Fig. 2.

We claim:

The ornamental design for a tap connector for electrical conductors, as shown.
